CORE CRIMPING MACHINE

Archibald G. Adams and Joseph Bertain, Three Rivers, Quebec, Canada, assignors to International Paper Company, New York, N. Y., a corporation of New York

Application September 28, 1934, Serial No. 745,917

7 Claims. (Cl. 93—83)

Our present invention relates to an apparatus for crimping the ends of fibrous cores commonly used in the news-print and other industries as the central core of large rolls of paper or other fabric. These cores are preferably made of paper wound upon itself into a very dense, rigid cylinder. The paper is relatively non-compressible and the resulting structure is so unyielding that tremendous force is required to dent or compress its surface. However, as is true of many materials which are relatively strong in compression, the paper is relatively poor in resistance, tearing and fracturing. Newsprint cores are provided with a slot at one end adapted to coact with a key on the shaft of the winding or unwinding mechanism. In the modern high speed machines, sudden shocks are quite often transmitted through these cores, and the key is liable to fracture the core and render it useless. For this reason the fibrous cores are provided with a metallic cap such as set forth in the patent to Phillip T. Dodge, #1,358,531.

It has heretofore been common practice to flare the flanges of such metallic caps in order that they may be slid lengthwise upon the end of the core. After the cap is seated it is compressed in an attempt to drive the outer flange into the material of the core so that its surface is flush with the outer surface of the core, to preserve a uniform diameter for even winding of the paper, or other fabric. The rigidity of the metal cap in combination with the rigidity of some cores often renders this impossible of achievement. A second method of seating core caps has been to preform the cap of very heavy sheet metal and drive the same onto the core in the hope that the cap would compress the fibres thereof as it was driven into place. This method proved unsatisfactory inasmuch as the cap would often gouge up a ridge of material, or would be flared outward from the surface of the core. In any event, the result was never uniform and perfect. A third method which was found better in some respects was to squeeze sections of the core between a pair of very strong squeezing jaws whose surfaces were curved to fit the curvature of the core. This proved unsatisfactory inasmuch as the small surface of the core under compression would tend to be fractured from the remaining free surface of the core. As the core would be rotated between the jaws for successive squeezing operations there would be formed numerous weakened or fractured areas. The ultimate result would sometimes be that a shock transmitted through the keyway of the metal cap fractured the entire end of the

core away from the remainder thereof. Applicants' present invention is a mechanism so devised as to overcome all of these objectionable features of past practice.

The invention comprises a number of radially disposed inner and outer jaws so devised that a uniform crimping pressure takes place throughout the entire surface of the end of the core, thereby preventing the formation of fractures and weakened spots. The inner and outer jaws are operated by the same impelling mechanism from which force is transmitted through a rigidly aligned head so that pressure at every part of the core will be evenly and simultaneously applied. The resulting crimped core may have a preformed cap slid thereon to form a capped core having a uniform outer diameter which is free from ridges, fractures and weakened portions.

Other objects and advantages of our invention will be apparent from the following specification taken in connection with the accompanying drawings wherein like numerals refer to like parts throughout. In the drawings:

Fig. 1 is an end elevation of our machine looking into the crimping throat;

Fig. 2 is a partial, vertical section taken along line 2—2 of Fig. 1 and illustrating details of a safety clutch which may be utilized, if desired;

Fig. 3 is a partial end view of the safety clutch illustrating the clutch in driving engagement;

Fig. 4 is a large scale view of the clutch dog;

Fig. 5 is a side elevation of the entire machine illustrating features thereof;

Fig. 6 is an elevation of an adjustable eccentric driving means comprising a portion of the mechanism;

Fig. 7 is a top plan view of the eccentric shown in Fig. 6;

Fig. 8 is a large scale, vertical section of the crimping mechanism, illustrating details thereof as the jaws are compressed and crimping the end of a core;

Fig. 9 is an end elevation of the inner crimping member showing details of the crimping jaws;

Fig. 10 is a vertical section taken along line 10—10 of Fig. 9;

Fig. 11 is a view similar to Fig. 8 but showing the jaws in open position as a core is presented thereto;

Fig. 12 is a vertical section taken along line 12—12 of Fig. 11 and showing details of the mounting and arrangement of the outer crimping jaws; and

Fig. 13 is a plan view of one of the outer crimping jaws.

Our invention comprises a suitable standard 20 upon which is located a driving shaft 21 driven by a pulley 22 keyed thereon. A pinion 23 keyed to shaft 21 drives a large gear 24 in order that the resulting movement of the crimping jaws may be as slow as desired. Gear 24 has a flange 25 integral therewith, which flange is provided with a series of internal notches 26. The gear 24 is loosely mounted upon a shaft 27 supported in the standard 20. Keyed to shaft 27 is a driven clutch member 28 comprising a disc with a dog seat 29 formed in its periphery. The inner end of the dog seat 29 is preferably extended inward in the form of a boss within which is seated the rounded end 30 of a clutch dog 31. The dog seat is so formed that the rounded end of the dog may be slid lengthwise into the boss and may have a limited rotative movement therein. The dog extends forwardly toward the periphery of the driven clutch member and is formed with an engaging portion 32 and a tab end 33. The engaging portion 32 is adapted to interlock with a notch 36 in the driving flange 25. Because of the very slow speed achieved through the reduction gearing the tab end 33 may be caught and held to cause disengagement of the clutch. The driven member 28 is formed with a small bore 34 having a locking pin 35 urged outwardly by a spring seated therein. The reduced end of the locking pin 35 fits into a groove 36 in the clutch dog and prevents endwise movement of the rounded end 30 in the boss of the dog seat. The clutch mechanism is a safety device and is normally never used due to the fact that the opening and closing of the crimping jaws continually takes place at such a speed that the operator can insert and remove cores as long as desired and as long as the machine is in use.

Shaft 27 extends through a bearing 40 mounted in the standard 20 and at its end is provided with a key engaging with and driving an adjustable eccentric 41. The eccentric is provided with a screw 42 and sliding block 43 by means of which an eccentric pin 44 may be given greater or lesser eccentricity. The eccentric pin 44 continually revolves about shaft 27 in one direction. A jointed pitman 45 connects the eccentric pin 44 to a crank 46 associated with the crimping head. The jointed pitman allows relative endwise movement of the crank 46 and the eccentric pin 44 for a reason which will presently appear. The crank 46 is in effect a large nut, having an arm integral therewith, which is screwed upon a threaded member 47. The eccentricity of the pin 44 is adjusted to give the desired component of movement of crank arm 46 above and below the horizontal, preferably a total of about 45 to 60 degrees of movement. The result is that for every complete rotation of pin 44 the crank 46 will be partially rotated relative to member 47 in a tightening direction and then partially rotated in the opposite or loosening direction. The member 47 is provided with a reduced forward portion defined by a shoulder 48. Keyed to this reduced portion is a jaw holding block 49 which prevents relative rotation of the member 47 and the standard 20 inasmuch as block 49 is fixed with respect to the standard 20 by means of set screws 50 in a surrounding sleeve 51 bolted to the standard. A cam ring 55 surrounds member 47 in abutting relation to block 49 and is followed by a sleeve 56 and a washer 57. A headed bolt 58 is provided with a reduced threaded end defining a shoulder which rigidly locks the washer 57 and members 56, 55, and

49 together and against shoulder 48. As a result of the rigid assembly of these members cam ring 55 is rigidly fixed with respect to the standard 20. This rigidity is assisted by a flange or shoulder 59 on block 49 engaging with a matching shoulder on the sleeve 51.

Between the washer 57 and the head of bolt 58 are mounted washers 60 and 61 between which is interposed an extremely strong spring 62 tending to spread the washers. An integral tubular jaw member 63 is positioned so as to surround the cam ring 55, the spacing ring 56 and the bolt 58. A flange 64 of this jaw member bears against spacing ring 56, and the forward tip 65 of the jaw member bears against a shoulder on block 49 to fix the jaw member radially with respect to the member 47. An internal flange 66 having an inclined cam surface is seated upon the cam ring 55. The greater portion of the jaw member 63 is longitudinally slotted as at 67 to define resilient jaws, each of which is connected to the others through the outer end of member 63. An outer flange 68 defines a limiting shoulder to define the extent to which the core 70 may be inserted into the crimping head. The inner surface of flange 68 is adapted to receive thrusts transmitted by the partial rotation of crank 46 to cause relative movement of member 63 and member 47. In Fig. 11 the jaws are open and a core 70 has been inserted against flange 68. In Fig. 8 the partial rotation of crank 46 has caused outward movement of member 63, as will hereinafter appear, thereby causing the cam surfaces 66 to ride upward on the cam ring 55 and causing spreading of the inner crimping jaws. Since it is not necessary that the inner portion of the core cap flange should lie flush with the inner surface of the core the crimping achieved thereby is greatest at the lip of the core and gradually decreases toward a point 71 preferably some distance inward from the outer crimping portion. The flange 64 bears against the washer 60 and compresses the spring 62 as shown in Fig. 8. The ultimate reversing movement of crank 46 will be paralleled by a returning movement of member 63 by reason of the expansion of spring 62 causing inward movement of the inner crimping jaws to the position of Fig. 11.

The mechanism for operating the outer crimping jaws and the structure thereof will now be described. A ring 75 is positioned against the inner face of crank 46. A thrust member 76 is close to ring 75 but does not contact therewith. Surrounding a flange of thrust member 76 are spaced rings 77 and 78 between which are located steel balls 79 confined in pockets or raceways in the adjacent faces of rings 77 and 78. A retaining collar 80 may be provided, if desired. Inward movement of ring 75 due to the partial rotation of crank 46 causes inward movement of thrust member 76, without rotation thereof because of the balls 79. The block 49 is provided with radially extending slots 81 within which are positioned the narrow hafts of a series of outer crimping jaws 82. The outer ends of the hafts of the crimping jaws are seated in an annular groove in the face of thrust member 76 in such a fashion that limited pivoting movement of the free ends of the jaw members may occur while a continual thrust will be transmitted longitudinally of the jaw members. A ring 83 surrounding member 47 and free to move relative thereto fits into notches in the jaw members 82 for a purpose which will presently appear. The jaw members contact the bottom of slots 81 at or

near point 84, and from point 84 to their free ends are reduced in depth so as to allow rocking movement of the jaw members within the slots 81. The free ends of the jaw members are provided with cam faces 85 matching a cam ring 86 bolted to the sleeve 51 so that relative movement of the jaw members 82 and the standard 20 will cause crimping of the outer surface of the core 70. Seated in reduced inward extensions of slots 81 are a series of thrust bars 90, one end of each bearing against the ring 83 and the other end of each being provided with a depending hook portion 91 designed to fit between the flange 68 of member 63 and the inner surface of block 49. The length of the portion 65 of member 63 is such as to allow normal freedom of movement of the hook portion 91, and a spring 92 seated in a socket in block 49 forces the hook portion 91 upward to the farthest extent allowed by movement of member 82 in the slot 81. Thus in the open position illustrated in Fig. 11 the outer jaws will be held open to receive a core. Surrounding member 47 are a series of spring pressed plungers 93 tending to force ring 83 away from block 49 and hence outwardly relative to standard 20.

The operation of the device will be understood best by the following statement. As crank 46 rotates, a movement and thrust is transmitted through the thrust member 16 and through the jaw members 82 whereupon the cam ring 86 will cause inward movement and crimping of the outer surface of the core. The movement of members 82 causes a corresponding movement of ring 83 which transmits the movement and thrust through members 90 and shoulder 68 to cause member 63 to move outwardly and the inner crimping jaws to ride up on cam ring 55 thereby simultaneously crimping the inner surface of the core. The amount of pressure applied to each section or jaw of the inner crimping member and to each of the outer crimping jaws is exactly the same at any given instance and the radial movement of each part is exactly the same, and also the inner jaws and the outer jaws have exactly the same lengthwise movement relative to standard 20. As the crank 46 reverses and loosens the jaws the position illustrated in Fig. 11 is attained by reason of spring 62 transmitting thrust through shoulder 64, shoulder 68, members 90 and ring 83. Since the outer jaw members 82 are hooked over ring 83 they will be drawn toward the left end of Fig. 11 and the springs 92 will cause members 90 to rock the jaws outward thereby opening the outer crimping members. The inner crimping jaws, due to their being resilient and connected to an integral end ring, will tend to open of their own accord as cam surfaces 66 slide downward on cam ring 55. The plungers 93 tend to prevent binding of ring 83 and assist the spring 62 in returning the parts to open position.

The outer jaw members are so fashioned as to compress the outer surface of the core evenly inward the distance desired, the tips of the jaws defining the shoulder 95 which is located preferably at the point where the outer flange of the metallic cap will terminate. For this reason the entire outer flange of the cap will lie in the plane of the outer surface of the core and flush therewith throughout its extent. The gradually decreasing compressed area of the inner surface of the core will provide the necessary wedging action to firmly unite the cap to the core.

The foregoing constitutes a preferred embodiment of our invention and we do not intend to

be limited to the exact details thereof, but claim as our invention any alterations, modifications and substitutions which may come within the scope of the following claims which are to be broadly construed.

We claim:

1. A core crimping machine comprising radially disposed inner and outer jaws adapted to crimp substantially the entire inner and outer surfaces of the end of a core, means to move each of said jaws in a longitudinal direction simultaneously and to the same extent, and stationary cams with which said jaws coact to cause crimping action thereof.

2. A core crimping machine comprising radially disposed inner and outer jaws adapted to crimp substantially the entire inner and outer surfaces of the end of a core, means to move each of said jaws in a longitudinal direction simultaneously and to the same extent, and stationary cams with which said jaws coact to cause crimping action thereof, said cams being so disposed that the crimping movement of each of said inner jaws and each of said outer jaws simultaneous and coextensive.

3. A core crimping machine comprising radially disposed inner and outer jaws adapted to crimp substantially the entire inner and outer surfaces of the end of a core, and means to move each of said jaws in a longitudinal direction simultaneously and to the same extent, and stationary cams with which said jaws coact to cause crimping action thereof, said means comprising positive mechanism for causing longitudinal movement in one direction during the crimping action and resilient means for causing longitudinal return movement.

4. A core crimping machine comprising radially disposed inner and outer jaws adapted to crimp substantially the entire inner and outer surfaces of the end of a core, and means to operate each of said inner jaws and ends of said outer jaws simultaneously and to the same extent, said means comprising a threaded member about which said jaws are mounted and a cooperating threaded crank adapted to cause longitudinal movement of said jaws as it is rotated about said threaded member.

5. A core crimping machine comprising radially disposed inner and outer jaws adapted to crimp substantially the entire inner and outer surfaces of the end of a core, and means to operate each of said jaws simultaneously and to the same extent, said means comprising a threaded member about which said jaws are mounted and a cooperating threaded crank adapted to cause longitudinal movement of said jaws as it is rotated about said first threaded member, an inner cam ring mounted upon said threaded member and an outer cam ring fixed with respect to said threaded member and said inner cam ring, and bevelled surfaces upon said jaws cooperating with said cam rings whereby longitudinal movement thereof causes outward movement of said inner jaws and inward movement of said outer jaws.

6. A core crimping machine comprising an outer cam ring and a concentric inner cam ring fixed with respect to said outer cam ring, concentrically mounted inner and outer crimping jaws cooperating with said inner and outer cam rings respectively, and means for causing relative movement of said jaws and said rings in a direction parallel to the axis thereof.

7. A core crimping machine comprising a threaded member, an outer cam ring and an inner cam ring fixed with respect to said outer cam ring, concentrically mounted inner and outer crimping jaws cooperating with said inner and outer cam rings respectively, and means for

causing relative movement of said jaws and said rings in a direction parallel to the axis thereof, said means comprising a crank threaded upon said member and means to oscillate said crank.
